(57) **CLAIM**

The ornamental design for a laptop case, as shown and described.

DESCRIPTION

FIG. 1 is a perspective view of a laptop case showing the upper portion of my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is a perspective views of a laptop case showing the lower portion of my new design;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an enlarged view of portion 19 shown in FIG. 11;

FIG. 20 is an enlarged view of portion 20 shown in FIG. 11;

FIG. 21 is an enlarged view of portion 21 shown in FIG. 11;

FIG. 22 is an enlarged view of portion 22 shown in FIG. 12;

FIG. 23 is a perspective view of the laptop case showing the upper and lower covers in an assembled state with a laptop put therein; and,

FIG. 24 is another perspective thereof.

The dash-dash broken lines in FIG. 17 are for the purpose of illustrating portions of the laptop case that form no part of the claimed design. The additional dash-dash broken lines

(Continued)

showing the laptop in FIGS. 23-24 are directed to environment that form no part of the claimed design. The dot-dashed broken lines in FIGS. 1, 9-10 and FIGS. 11-12, 19-22 show the boundaries of the enlarged portions and forms no part of the claimed design.

1 Claim, 24 Drawing Sheets
